[57] **CLAIM**

The ornamental design of a food processor power unit, substantially as shown and described.

DESCRIPTION

FIG. 1 is a top front perspective view of a food processor power unit showing my new design;

FIG. 2 is a top plan view thereof;

FIG. 3 is a front elevation view thereof;

FIG. 4 is a rear elevation view thereof; and

FIG. 5 is an elevation view thereof as seen from the opposite side from FIG. 1.

The broken lines representing the food processor container member are shown for illustrative purposes only.

FIG-1

FIG-2

FIG-3

FIG-4

FIG-5
